UNITED STATES PATENT OFFICE.

OTTO R. LINDSTAEDT, OF INDIANAPOLIS, INDIANA.

DISPLAY-RACK FOR BED MATTRESSES AND SPRINGS.

1,391,484.

Specification of Letters Patent. Patented Sept. 20, 1921.

Application filed January 26, 1920. Serial No. 354,121.

To all whom it may concern:

Be it known that I, OTTO R. LINDSTAEDT, a citizen of the United States, residing at Indianapolis, in the county of Marion and State of Indiana, have invented a new and useful Display-Rack for Bed Mattresses and Springs, of which the following is a specification, reference being had to the accompanying drawings and to the letters and figures of reference marked thereon.

This invention relates to a rack or stand on which samples of bed mattresses and bed springs or other articles may be compactly arranged and conveniently displayed to prospective purchasers in stores or factories, the invention having reference more particularly to a rotary rack having a plurality of shelves or frames adapted to support and hold the articles to be displayed.

An object of the invention is to provide an improved rack which shall be so constructed as to be capable of holding a large number of bed mattresses or bed springs so as to be displayed one at a time, and on the minimum floor space.

Another object is to provide a strong and easily operated rotary display rack for bed mattresses which shall be so constructed as to permit examination of the tops and bottoms of the mattresses.

A further object is to provide a display rack of large capacity for bed mattresses or various other articles of merchandise and enable a salesman or demonstrator to alone bring each article easily into view or convenient display position.

A still further object is to provide a display rack of large capacity which may be simply and inexpensively constructed compactly and which shall be durable and economical in use.

With the above-mentioned and other objects in view, the invention consists in a rotary rack having a plurality of radial arms of such construction as to constitute shelves or bed frames of open-work or skeleton-like formation to support articles without obscuring them, each shelf or bed frame being provided with an open-work or skeleton-like clamp which is removably and preferably adjustably connected therewith so as to hold articles of different thickness; and the invention consists also further in the parts and combinations and arrangements of parts

as hereinafter particularly described and further defined in the accompanying claims.

Referring to the drawings,—Figure 1 is an end elevation, partially broken away, of the improved display rack; Fig. 2 is a fragmentary section of the rack and particularly a plan of one of the plurality of bed frames thereof; Fig. 3 is a front elevation of the display rack; Fig. 4 is a fragmentary sectional detail illustrating the mounting of the clamp with which each bed frame is provided; Fig. 5 is a fragmentary elevation illustrating a suitable type of brake adapted to stop rotation of the rack; and, Fig. 6 is a fragmentary sectional detail of a latch of suitable construction to prevent rotation of the rack for the purpose of steadily holding an article in suitable position to be displayed.

Similar reference characters in the different figures of the drawings indicate corresponding elements or features of construction herein referred to in detail.

In practically carrying out the objects of the invention a suitable support for a rotary holder is provided and preferably is in the form of a stand comprising a suitable base frame 1 and standards 2 and 3 thereon. The rotary carrier includes a substantially cylindrical spider which has two heads or ends 4 and 5 provided respectively with journals 6 and 7 which preferably are integral with a shaft 8, and a shell 9 secured to the heads or ends, the shell preferably being composed of wooden slats so as to constitute a hollow cylinder, the journals 6 and 7 of which are mounted on the standards to permit rotation of the cylinder which constitutes the core of the rack.

The rack has a suitable number of open-work or skeleton bed frames, preferably an even number as twelve equi-distantly spaced apart, as at 10, radially arranged on the core, in order that the rack shall be nearly balanced and easily controlled, to support and carry articles to be displayed and examined. Each bed frame comprises two arms 22 and 23 rigidly secured at one end to the shell 9 at the heads 4 and 5 respectively, a cross bar 24 connected with the opposite ends of the arms, and a suitable number of widely separated slats 25, arranged beyond the plane of one side of the frame arms, each slat having upturned hangers 28 and 29

on its opposite ends respectively, one hanger of each slat being secured to the shell 9 and the other to the cross bar 24, so that a mattress or bed spring frame may rest on the 5 slats and be retained within the frame; and, preferably the frame is provided with a supporting beam or bar 30 secured to the under sides of the slats and having upturned hangers 31 and 32 on its ends that are secured 10 to the arms 22 and 23 respectively, to prevent the slats from sagging. Two annular braces or truss rings 33 and 34 are provided which are arranged concentrically to the journals and secured to the bed frames, 15 one being secured to all the arms 22 opposite to the hangers 31 and the others secured to all the arms 23 opposite to the hangers 32. One truss ring has a suitable number of sockets 35 and 35', the other ring having 20 sockets 36 and 36', the sockets preferably extending through the rings and being arranged at suitable distances from the bed frame arms in proximity to one side thereof.

A suitable number of open-work or skeleton clamps is provided, one for each bed frame, and they preferably comprise similar main bars 37, arranged as indicated, each bar having a stud or projection 38 on one end thereof to be inserted into either socket 30 36 or 36', the opposite end of the bar being provided with a movable lock bolt 39 adapted to be inserted into either one of the sockets 35 or 35'; and the main bar has a suitable number of cross bars 40, 41, 42, 35 thereon that lie approximately on a plane parallel to the plane of the slats at a suitable distance from the slats to clamp a mattress or a bed spring thereto, the clamps being adjustable to the different sockets to suit articles of different thickness.

The stand of the rack is provided with a suitable pivot stand 43 to which a latch lever is pivoted between its ends so as to have an arm 44 which is provided with a 45 holding crotch or fork 45 adapted to engage the cross bar 24 of either one of the bed frames when brought thereto, and a controlling arm 46 which extends adjacent to the standard 2 and is held in place at either 50 side of a lock lug 47 mounted on the stand. The latch enables the salesman or demonstrator to prevent movement of the rack after it has been adjusted as desired, in case the articles do not happen to be arranged to balance the rotary holder.

In order that the rack may be conveniently stopped after it has been rotated, a suitable brake preferably is provided and may suitably comprise a spring arm 48 secured to the inner side of the standard 2 and extending over to the outer face of the ring 33, being preferably provided with a filling block 49 having the form of a wedge and arranged in a suitable guide 50 secured 65 to the standard, an oppositely arranged

wedge 51 being arranged between the filling block and the standard and connected to a lever 52 which is pivoted between its ends to a suitable pivot 53 mounted on the standard 2.

A bed mattress 54 is indicated by broken lines in one of the bed frames, and a bed spring 55 is indicated by broken lines in another one of the bed frames.

In practical use the salesman or demonstrator and the purchaser may stand in proximity to the standard 2 at which position the brake lever 52 and the latch lever 46 will be found conveniently accessible and the articles, such as a bed mattress, a bed spring, or a pile of rugs may be examined when in the frames positioned as at 13 or 14, and the skeleton clamps will permit the articles to be turned up at the outer corners thereof to permit the under side to be examined. Also articles in the frames positioned as at 12 and 15 could be seen. The customers obviously may walk to the opposite side of the rack and more fully examine the under side of the articles which would be found inverted in a different position of the frames. When it is desired to bring other articles or a certain article in a frame to convenient position, the rack is suitably rotated by hand and may be stopped by application of the brake, after which the latch fork 45 may be brought into engagement with a downward extending arm or bed frame to lock the rack against further rotation. When it is desired to change the samples of articles the clamps may be removed by first withdrawing the latch bolt 39 thereof and then withdrawing the stud or projection 38 from its socket, the reverse operation being performed to clamp a new sample in a frame or carrying arm of the rack.

Having thus described the invention, what is claimed as new is—

1. A display rack including two standards, a shell rotatively supported by the standards, bed frames rigidly secured to the shell and provided with clamps arranged opposite to and beyond the front of the frame, two annular braces secured to all the bed frames, and means for securing the clamps to the two annular braces.

2. In a display rack, the combination of a stand, a shell rotatable on the stand, and a plurality of bed frames comprising each a pair of arms secured at one end to the shell and a cross-bar connected to the opposite end of the arms, slats having each a hanger secured to the shell and a hanger secured to the under side of the slats and having hangers secured to said arms respectively.

3. In a display rack, the combination with a pair of standards, of a shell rotatably supported by the standards, bed frames secured to the shell and provided with clamps

arranged opposite to and beyond the front of the frame, two annular braces secured to all the bed frames, a movable brake device supported to coöperate with one of the standards and one of the annular braces, and a movably supported latch device having a crotch to engage either one of the bed frames when brought thereto.

4. A display rack comprising two standards, a shell rotatably mounted on the standards, a plurality of open-work bed frames rigidly secured at one side to the shell and extending radially therefrom, two brace rings secured to opposite ends respectively of the bed frames and having each

a plurality of sockets in the inner side thereof in proximity to the frames, and a plurality of skeleton-like clamps arranged opposite to the bed frames respectively, each clamp having a stud arranged in a socket 20 in one of the braces and a lock bolt extending into a socket in the remaining one of the braces.

In testimony whereof, I affix my signature in presence of two witnesses.

OTTO R. LINDSTAEDT.
